(57) **CLAIM**

The ornamental design for an electrical connector, as shown and described.

DESCRIPTION

FIG. 1 is a bottom, right side perspective view of an electrical connector, showing my new design;

FIG. 2 is a rear, left side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side view thereof;

FIG. 8 is a left side view thereof; and,

FIG. 9 is a sectional taken along line 9-9 as depicted in FIG. 3.

The dash-dash broken lines in the drawings are for the purpose of illustrating portions of the article that form no part of the claimed design.

The dash-dot broken line represents the cross-section and forms no part of the claimed design.
